MAGNETIC STRUCTURE

Leslie J. Anderson, Moorestown, N.J., assignor to Radio Corporation of America, a corporation of Delaware

Filed June 1, 1954, Ser. No. 433,634

2 Claims. (Cl. 179—115.5)

This invention relates to magnetic circuits, and more particularly to magnetic structures associated with ribbon type microphones.

In constructing many types of ribbon microphones, it is often necessary to have proper spacing between magnetic members. A small variation in the dimensions of the magnets used often results in inefficiency in the microphone. In the construction of such ribbon types of microphones, critical tolerances of the parts are, therefore, often involved.

In many types of magnetic structures associated with ribbons in ribbon microphones, the space between the magnets within the magnetic structure and the ribbon may be as little as .002 of an inch. It is important, therefore, that magnets not be so large as to lessen this air gap, since an interference with the free movement of the ribbon may result. It is also important that the air gap between the magnets and the ribbon not be too great, as would be the case if the magnets are too small, since the sensitivity of the microphone resulting from the structure would be greatly impaired. For example, if the space between the ribbon and the magnet is .005 of an inch instead of .002 of an inch, the sensitivity of the microphone would be reduced approximately 50 percent.

In accordance with the present invention, a small efficient magnetic circuit for a ribbon type microphone is provided, without involving critical tolerances of the parts. A pair of L or U-shaped members of substantially the same size is provided in a magnetic structure, each member having a magnet suitably attached thereto. These members provide the yoke pieces for the magnets and are mutually movable so as to provide accurate control of the air gap between the magnets. The assembly of the magnetic structure is accomplished by inserting a gauge of proper size in the air gap between the two magnets and overlapping portions of the U or L-shaped members. When the proper spacing has been provided, the overlapped L or U members are clamped in place. The members are then soldered, or otherwise suitably fixed to each other, thereby maintaining the desired air gap between the magnets within the magnetic structure.

It is an object of this invention to provide a small, efficient magnetic circuit, which does not involve critical tolerances of the parts utilized in the circuit.

It is a further object of this invention to provide a small, efficient magnetic structure for use in a ribbon type microphone.

It is a still further object of this invention to provide a method of manufacturing a magnetic structure, which does not involve critical tolerances of the parts included in the structure.

Other objects and advantages of the present invention will become apparent and suggest themselves to those skilled in the art to which the invention relates, from a reading of the following specification in conjunction with the accompanying drawings, in which:

Figure 1 is a view, in front elevation, of a magnetic

structure utilizing a pair of L-shaped members in accordance with the present invention;

Figure 1-a is a top plan view of the construction shown in Figure 1;

5 Figure 1-b is a view, in side elevation, of the magnetic structure shown in Figure 1;

Figure 2 is a view, in front elevation, of a magnetic structure utilizing a pair of U-shaped members in accordance with the present invention; and

10 Figure 3 is an elevational view, partly in section, of a ribbon type microphone utilizing a pair of U-shaped members in accordance with the present invention.

Referring to Figures 1, 1-a and 1-b, a pair of magnets 10 and 12 are soldered or otherwise suitably attached to a pair of L-shaped magnetic members 14 and 16, respectively. The L-shaped members provide the yoke assembly for the magnetic structure. The L-shaped members may be slightly tapered, as indicated to improve the efficiency of the magnetic circuit. The magnets have pole ends adapted to define an air gap and may also be tapered at these pole ends towards the air gap, as indicated, to improve the efficiency of the magnetic circuit. A ribbon conductor may be suitably mounted and supported in the air gap between the magnets as shown in the structure of Figure 3. In carrying out the invention, a gauge of the proper size may be inserted in the air gap. The L-shaped members, being mutually slidable, are moved until the proper spacing of the air gap is attained. The members are then 25 clamped in place and solder is applied to points 18 and 20, or other suitably holding means employed, to maintain the magnets in a desired spaced relationship.

Referring to Figure 2, the magnetic structure shown comprises a pair of magnets 22 and 24 suitably attached 30 to a pair of U-shaped magnetic members 26 and 28. In assembly the structure, a gauge, shown here as two circular rods 30 and 31 are inserted in the air gap between the magnets. When the desired spacing is attained by moving the members 26 and 28 until the magnets come 35 into physical relationship with the gauge, the members may be clamped in place. Heat and solder may then be applied to points 32, 34, 36 and 38 to maintain the magnets in a fixed spaced relationship.

Referring now to Figure 3, a ribbon type microphone 40 comprises a ribbon conductor 40 suitably disposed between a pair of magnets 42 and 44. The magnets are suitably attached to a pair of U-shaped magnetic members 46 and 48. The ribbon is electrically connected to a transformer 50 through the leads 52, 54 and 56. 45 The leads 52 and 56 are provided, in a known manner for balance. The electrical output of the transformer is coupled to a utilization circuit (not shown) through a cable 58. The U-shaped members are fixed to each other by means of solder 60 and 62, or by any other suitable means. The assembly of the magnetic structure of this ribbon type microphone is in accordance with the assembly previously described in connection with Figures 1 and 2. The entire microphone is suitably fixed to a base 64 and has a cover, or perforated screen, 66.

50 In assembly of the magnetic structure of Figure 3, the magnets 42 and 44 first are suitably attached to the intermediate portions 68 and 70, respectively, of the U-shaped members, or yoke pieces 46 and 48, respectively. The magnets are disposed on the intermediate portions of the members between the top and bottom portions of the U-shaped members, with the top and bottom portions extending outwardly further from the intermediate portions than the magnets. The increased width of the top and bottom portions of the members permit 55 an overlapping of the top and bottom portions of one member with top and bottom portions of the other member, while still maintaining an air gap between the mag-

nets. When the proper size of the air gap is attained, by the insertion of a gauge between the magnets, for example, suitable means are employed to maintain the air gap between the magnets by physically attaching the members to each other.

It is seen that the present invention provides a pair of mutually movable yoke pieces whereby accurate control of the air gap without critical tolerances on the parts is attained.

The magnetic structure involved in this invention is 10 relatively simple and inexpensive to construct. The cost of constructing a ribbon microphone, where an accurate control of the air gap between the magnets is necessary, is considerably reduced when the magnetic structure, embodying the present invention, is used.

What is claimed is:

1. A magnetic structure comprising a pair of U-shaped elements, each of said elements having top, bottom and intermediate portions, a pair of permanent magnets, means for attaching a different one of said magnets to 20 each of said intermediate portions of said elements, said top and bottom portions of each of said elements extending in the same direction beyond said magnets, said elements being disposed with the top and bottom portions of one of said elements overlapping the top and bottom 25 portions of the other of said elements and with said magnets opposed to each other to define an air gap therebetween, and means for securing said elements in fixed relationship with each other whereby the dimensions of said air gap between said magnets are fixed.

2. A ribbon type microphone having a magnetic structure comprising a pair of U-shaped members each having a pair of legs, a pair of permanent magnets each secured to a different one of said members between the legs 30

thereof, said members being disposed with portions of one of said members overlapping portions of the other of said members and to provide an air gap between said magnets, means for securing said members in fixed relationship, and a ribbon conductor disposed within said air gap between said magnets.
